US0D1060425S

(12) **United States Design Patent** (10) Patent No.: **US D1,060,425 S**
(45) Date of Patent: ** Feb. 4, 2025

(54) **DISPLAY SCREEN OR PORTION THEREOF WITH ICON**

(71) Applicant: **Yokogawa Electric Corporation**,
Tokyo (JP)

(72) Inventors: **Jasper Bryan S. Ratilla**, Singapore
(SG); **Yasunori Okazaki**, Musashino
(JP); **Kan-E Kuriyama**, Musashino
(JP)

(**) Term: **15 Years**

(21) Appl. No.: **35/518,680**

(22) Filed: **Oct. 17, 2022**

(80) **Hague Agreement Data**

Int. Filing Date: **Oct. 17, 2022**

Int. Reg. No.: **DM/224393**

Int. Reg. Date: **Oct. 17, 2022**

Int. Reg. Pub. Date: **Oct. 20, 2023**

(51) **LOC (15) Cl.** **14-04**

(52) **U.S. Cl.**

USPC **D14/491**

(57)

CLAIM

The ornamental design for a display screen or portion thereof with icon as shown and described.

DESCRIPTION

1. Display screen or portion thereof with icon

1 : Front

The peripheral dashed broken lines depict a display screen or portion thereof and form no part of the claimed design.

1 Claim, 1 Drawing Sheet

US D1,060,425 S
